Inventor
Samuel Tembey.

By *James Taylor*
Atty.

UNITED STATES PATENT OFFICE.

SAMUEL TEMBEY, OF NANAIMO, BRITISH COLUMBIA, CANADA.

TRIP DEVICE FOR PREVENTING BREAKAGE OF TRANSMISSION ROPES.

Application filed October 30, 1924. Serial No. 746,907.

To all whom it may concern:

Be it known that I, SAMUEL TEMBEY, a subject of the King of Great Britain, and a resident of the city of Nanaimo, in the 5 Province of British Columbia, Canada, have invented certain new and useful Improvements in Trip Devices for Preventing Breakage of Transmission Ropes, of which the following is a specification.

10 My invention relates to improvements in trip devices for preventing the complete breakage of transmission ropes, and the object of my invention is to provide a simple, inexpensive, and easily installed device 15 adapted to be operated practically instantaneously by the rope when a strand of the same breaks to shut off the power and stop the operation of the driver, thus preventing the complete breakage of the rope and enabling it to be readily repaired and operations resumed without any undue delay.

I attain this object by the construction illustrated in the accompanying drawings in which—

25 Fig. 1 is a side view of my device.

Fig. 2 is a plan view.

Similar figures of reference indicate similar parts in the views.

1 indicates the rope pulley, the driver, the 30 direction of its rotation being indicated by the arrows in Fig. 1. Disposed transversely across the face of the pulley and in close proximity thereto is a rod 2 formed as a crank as to its ends 3 and 4 and arranged 35 normally in a horizontal position, the ends 3 and 4 being freely supported in suitably secured bearings 5 and 6, and one end, 3, is bent at right angles and extended, as at 7, to carry a counterweight, 8, while the opposite end, 4, is bent to provide an inwardly and downwardly inclined arm 9 the outer end of which is jawed, as at 10.

11 indicates a link pivotally hung at and to a suitable place by a pin 12 secured into 45 the upper end of the link, which link is provided intermediate its length and at its lower end with pins 13 and 14 respectively, and is connected to the arm 9 by a connecting rod 15 attached at its opposite ends respectively to the jaw 10 of the arm 9 and the lower pin 14.

16 indicates the governor lever which when moved in the direction of the arrow about its pivot 17 draws the rod 18 in the 55 same direction and operates the governor valve to shut the steam off the engine, the

lower end of which lever 16 is normally in contact with the upturned end 19 of a lever 20 pivoted adjacent its outer end on a suitably secured pivot 21 while its opposite end 60 rests on the intermediate pin 13 of the link 11, and at a suitable point in the length of this lever 20 is hung a counterweight 22, as shown in Fig. 1.

It will, of course, be understood that the 65 complete device is assembled and supported in approved mechanical manner.

In use the crank is disposed horizontally with the member 2 lying close to the rim of the pulley 1 and the end of the lever 20 70 resting on the pin 13, the link 11 being vertical and the entire device being arranged as indicated by the full lines in Fig.

1. On a strand of a rope becoming loose 75 it flies out as the pulley rotates and strikes the rod 2 immediately, knocking it upwardly, thus drawing the link 11 forwardly so that the pin 13 is drawn from under the end of the lever 20, which falls downwardly and swings the end 19 around on its pivot 21, 80 thus moving the governor lever 16 in the direction of the arrow and closing the valve, all as indicated by the dotted lines in Fig. 1, so that the steam is shut off the engine 85 practically coincidently with the stranding off the rope, thereby preventing its stranding any further with consequent complete breakage.

From the foregoing it will be seen that I have devised a simple means for preventing 90 breakage of transmission ropes, which is easily installed and maintained, and which accomplishes its object in a highly practical and efficient manner.

What I claim as my invention is:—

1. A trip device for preventing complete breakage of transmission ropes after partial breakage comprising, a weighted lever upturned and pivoted at one end, withdrawable means maintaining said lever normally horizontal, and means adapted to be actuated by an outflying rope strand to withdraw the withdrawable means clear of the lever.

2. A trip device for preventing complete breakage of transmission ropes after partial breakage comprising, a lever upturned and pivoted at one end weighted intermediate its length, a vertical link pivoted at its upper end having a pin intermediate its length on which the free end of said lever is supported maintaining it normally horizontal, and means adapted to be actuated by

an outflying rope strand to swing the link and carry its intermediate pin clear of the lever.

3. A trip device for preventing complete
5 breakage of transmission ropes after partial
breakage comprising, a lever upturned and
pivoted at one end weighted intermediate its
length, a vertical link pivoted at its upper
10 end having a pin intermediate its length
on which the free end of said lever is sup-
ported maintaining it normally horizontal, a
rod disposed transversely in close proximity
15 to the transmission rope driving pulley
rim having crank ends supported in suit-
ably mounted bearings, one of said ends
being bent to form an arm, and a connecting
rod between said arm and the lower end of
the vertical link.

4. A trip device for preventing complete

breakage of transmission ropes after partial 20
breakage comprising, a lever upturned and
pivoted at one end weighted intermediate its
length, a vertical link pivoted at its upper
end having a pin intermediate its length on
which the free end of said lever is supported 25
maintaining it normally horizontal, a rod
disposed transversely in close proximity to
the transmission rope driving pulley rim
having crank ends supported in suitably
mounted bearings, one of said ends being 30
bent to form a right angled extension and
provided with a counterweight and the other
to form an arm, and a connecting rod be-
tween said arm and the lower end of the
vertical link.

Dated at Nanaimo, B. C. this 11th day of
October, 1924.

SAMUEL TEMBEY.
